UNITED STATES PATENT OFFICE.

JOSEPH WHITEHEAD, OF PATERSON, NEW JERSEY, ASSIGNOR TO CROMPTON & KNOWLES LOOM WORKS, A CORPORATION OF MASSACHUSETTS.

JACQUARD FOR LOOMS.

1,174,917.

Specification of Letters Patent.

Patented Mar. 7, 1916.

Application filed January 11, 1913. Serial No. 741,468.

To all whom it may concern:

Be it known that I, JOSEPH WHITEHEAD, a citizen of the United States, residing at Paterson, in the county of Passaic and State 5 of New Jersey, have invented certain new and useful Improvements in Jacquards for Looms, of which the following is a specification.

My invention relates to jacquards for 10 looms, and the object of my invention is to improve upon the construction of a jacquard as ordinarily made.

In jacquards as ordinarily made, there is 15 a top griff or lifter plate, which has a vertical up and down movement, and comprises a series of plates or bars, extending transversely through the jacquard frame, and between different sets or series of upright wires or wire lifter hooks, which act to separate the same and hold them in proper relative position. There is also a stationary 20 bottom griff, comprising a series of bars extending transversely through the jacquard frame, and parallel to the plates or bars of the top griff. The bars of the bottom griff 25 extend between the different sets or series of upright wires or wire lifter hooks, and act to separate the same and hold them in proper relative position.

30 In my improved construction I provide an additional set of rods or wires, extending transversely through the frame, in a direction at right angles to the griff plates or bars, which rods extend between the different sets of upright wires or wire lifter hooks, to hold them in their proper relative position. This supplemental set of wires or rods are preferably connected to the movable top griff, to have a vertical up and down movement 35 therewith between the upright wires or wire lifter hooks, to guide and hold the same in their proper relative position, and to prevent said lifter hooks from becoming crossed during the operation of the jacquard, which 40 crossing is liable to happen, and which interferes with the proper operation of the upright wires, and causes imperfections to be made in the woven fabric.

My invention consists in certain novel features of construction of my improvements, 45 as will be hereinafter fully described.

I have only shown in the drawing a detached portion of a jacquard of ordinary construction, with my improvements com-

bined therewith, sufficient to enable those skilled in the art to understand the construction and operation thereof.

Referring to the drawing:—Figure 1 is a vertical cross section of a jacquard, on line 1, 1, Fig. 2, looking in the direction of arrow 60 *a*, same figure, and Fig. 2 is a side view of the parts shown in Fig. 1, looking in the direction of arrow *b*, same figure.

In the accompanying drawing, 1 is the end frame or stand of the jacquard, 2, Fig. 2, is 65 a stand having a hub 2' thereon, which is mounted to slide up or down on a vertical guide rod 3, Fig. 1, which is supported on the frame 1.

Secured to the stand 2 is the movable top 70 griff, or hook lifter plate 4, which has a vertical up and down motion communicated thereto, through a connector 5, which is pivotally attached at one end to a stud 5', secured in an arm 2" on the hub 2' of the 75 stand 2, see Fig. 2.

Secured to the side griff plate 4, only one plate 4 is shown in the drawing, is a series of plates or bars 6, which extend transversely through the jacquard frame, and between 80 the different sets of upright wires or lifter hooks 7, which have the upper hooked end 7', and the lower hooked end 7", as shown in Fig. 1. On the upward movement of the top griff, the plates 6 are adapted to engage 85 the hooks 7' on the upright wires 7 which are not moved out of the path of said plates by the pattern indicating mechanism, to raise said hooks with said plates.

The supplemental bottom griff plate 8 has 90 a series of transverse bars 8' thereon, which extend transversely through the jacquard frame, and between the different sets or series of upright wires 7, and parallel to the plates 6 of the top griff 4. The hooks 7" on 95 the upright wires 7 are adapted to rest on the bars 8', to hold said wires in their lowered position, as shown in Fig. 1.

All of the above mentioned parts may be 100 of the ordinary and well known construction.

I will now describe my improvements. In addition to the plates or bars of the movable top griff and the stationary bottom griff, which extend transversely through the jacquard frame between the different sets or series of upright wires or lifter hooks, as 105 above described, I provide a supplemental

set of rods or wires 11, which extend transversely through the jacquard frame, at the upper part thereof, between the different sets or series of upright wires or lifter hooks 7, 5 and in a direction at right angles to the bars on the movable top griff and the stationary bottom griff.

The rods or wires 11 may be stationary and attached to the jacquard frame, but in 10 this instance they are movable with the top griff, and are supported on rods 10, which extend in this instance through eyes 11' on each end of the wires 11 and are supported in the lower ends of hangers or brackets 9, 15 secured in this instance to the outer plates or bars 6 of the top griff 4, see Fig. 1.

The transverse rods or wires 11 act to keep the upright wires or lifter hooks 7 in their proper relative position, and prevent them 20 from crossing each other or getting out of alinement, when moved by the indications of the pattern surface, or when otherwise moved.

It will be understood that the details of

construction of my improvements may be 25 varied if desired.

Having thus described my invention, what I claim as new and desire to secure by Letters Patent is:—

The combination, in a jacquard machine, 30 of longitudinal rows of lifters, hooked at their upper free ends, a set of vertically reciprocating griff bars for engaging the upper hooked ends of the selected lifters and raising the same to form a shed, and separator rods, carried by and moving with said griff bars, and located closely adjacent vertically thereto, said separator rods being interposed between the longitudinal rows of lifters, and disposed at a right angle to the, 35 40 griff bars, whereby they serve to prevent engagement of the upper hooked ends of said lifters, by reason of lateral vibration of the same.

JOSEPH WHITEHEAD.
